UNITED STATES PATENT OFFICE.

WILLIAM W. ROBERTSON, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

TUBE-FRAME MECHANISM.

Application filed December 27, 1923. Serial No. 683,046.

To all whom it may concern:

Be it known that I, WILLIAM W. ROBERTSON, a subject of the King of Great Britain, residing at Worcester, in the county of 5 Worcester and State of Massachusetts, have invented a new and useful Tube-Frame Mechanism, of which the following is a specification.

This invention relates to Axminster carpet looms and particularly to means for transporting the tube frames and successively presenting them in weaving position. Difficulty has been encountered with the mechanism heretofore commonly used for 15 this purpose, as the tube frames have sometimes become accidentally detached from the transporting chains, and the supporting brackets and attaching springs have been found subject to occasional breakage. An 20 application has been previously filed in the name of Arthur P. Paine, on which Patent No. 1,493,561, issued May 13, 1924, in which rigid members depending from the chain links are attached to the tube frame by 25 sliding plungers or latches enclosed within the tube.

It is the object of my invention to improve the construction therein shown by providing means for accurately guiding the 30 depending members as they approach the position in which the tube frames are attached to the chains.

To this end, I provide discs rotatable with the chain driving sprockets and engaging the depending members on one side thereof and I also provide fixed arms engaging the other sides of the depending members as 35 they approach the position in which they cooperate with the tube frames for attachment thereof.

My invention further relates to arrangements and combinations of parts which will be hereinafter described and more particularly pointed out in the appended claims.

45 A preferred form of the invention is shown in the drawings in which

Fig. 1 is a front elevation of a portion of a yarn tube frame, together with attaching and transporting devices therefor;

50 Fig. 2 is a side elevation of the parts shown in Fig. 1;

Fig. 3 is a detail sectional view, taken along the line 3—3 in Fig. 1, and

Fig. 4 is a perspective view of one of the 55 tube frame holding devices.

Referring to the drawings, I have shown a chain driving shaft 10 having sprockets 11 fixed thereon and intermittently actuated by driving mechanism (not shown) to present yarn tube frames 12 successively in the 60 position indicated in Fig. 2.

Rigid members 13 are attached to alternate links of the transporting chains 14 and are provided with openings 16 and longitudinal slots 17 at their outer ends. The 65 members 13 are received in sockets 18 and are secured therein by latches or plungers 20 slideable in bearings within the tube frame 12 and yieldingly pressed outward by springs 21. Holding arms or devices 22 are 70 mounted in the usual manner in the loom to which the mechanism pertains and are actuated to move inward to receive and detach the tube frames and to thereafter present the tube frames to the warps. A lug 75 or projection 23 in the member 22 engages the plunger 20 and presses the same inward to detach the members 13 before the tube frame is moved downward toward the 80 warps.

The parts thus far described are substantially of the form shown in the prior application of Paine and in themselves form no part of my present invention.

A second lug or projection 24 is provided 85 to engage the upper surface of the socket 18 as the holding device 22 moves downward, thus positively withdrawing the tube frame from the rigid members 13.

It is essential for successful operation of 90 this type of tube frame mechanism that the member 13 should be accurately positioned laterally when a tube frame is to be attached thereto and for this purpose I have provided the guiding devices shown in Figs. 95 1 and 2.

At each side of the loom and at the outer side of each member 13, as it approaches attaching position, I provide a fixed arm 25 mounted on a portion 26 of the loom frame 100 and closely engaging the members 13 on the outer sides thereof. I also provide a disc

27 mounted on the shaft 10 and preferably rotatable with the sprocket 11. This disc engages the members 13 on the inner side and presses them outward against the fixed 5 arm 25.

The members 13 are thus held from lateral displacement in either direction and are accurately aligned with the sockets 18 as the tube frames are returned to attaching 10 position. It will be understood that the rigid members 13 are offset as shown in Fig. 1 merely for the purpose of clearance.

Having thus described my invention and the advantages thereof, I do not wish to be 15 limited to the details herein disclosed otherwise than as set forth in the claims, but what I claim is:—

1. In a loom, a transporting pattern 20 chain, a yarn tube frame, a rigid attaching member permanently secured to said chain and depending therefrom, a yielding attaching member carried by said tube frame and co-operating with said rigid member to detachably secure said tube frame to said 25 chain, and means to guide said member laterally as the parts approach attaching position.

2. In a loom, a transporting pattern 30 chain, a yarn tube frame, a rigid attaching member permanently secured to said chain and depending therefrom, a yielding attaching member carried by said tube frame and cooperating with said rigid member to detachably secure said tube frame to said 35 chain, and guiding means engaging both sides of said member to laterally position said member as the parts approach attaching position.

3. In a loom, a transporting pattern 40 chain, a yarn tube frame, a rigid attaching

member permanently secured to said chain and depending therefrom, a yielding attaching member carried by said tube frame and cooperating with said rigid member to detachably secure said tube frame to said 45 chain, a fixed arm to engage said member on one side as it approaches attaching position, and means to hold said member against said arm.

4. In a loom, a transporting pattern 50 chain, a yarn tube frame, a rigid attaching member permanently secured to said chain and depending therefrom, a yielding attaching member carried by said tube frame and cooperating with said rigid member to detachably secure said tube frame to said chain, a sprocket for said chain, a disc on said sprocket to engage one side of said attaching member, and an arm fixed to engage the other side of said attaching 55 member to position said member laterally as said member approaches attaching position.

5. In a loom, transporting pattern chains, a yarn tube frame, rigid attaching members permanently secured to said chain and depending therefrom, yielding attaching members carried by said tube frame and cooperating with said rigid members to detachably secure said tube frame to said 60 chains, and holding arms for supporting a detached tube frame, each of said arms having a projection thereon engaging a portion of said tube frame to positively detach said tube frame from said rigid members.

In testimony whereof I have hereunto affixed my signature.

WILLIAM W. ROBERTSON.
